UNITED STATES PATENT OFFICE.

GEORGE C. SCHMIDT AND FRANS G. D. MULLER, OF HOUSTON, TEXAS.

COMBINATION TANK VENT, FLAME ARRESTOR, AND AUTOMATIC SNUFFER.

Application filed March 30, 1925. Serial No. 19,385.

This invention relates to new and useful improvements in a combination tank vent, flame arrester and automatic snuffer.

One object of this invention is to produce 5 an apparatus of the character described specially designed for use in connection with vapor tight tanks, or reservoirs containing evaporative fluids such as crude petroleum or its derivatives, and whereby the pressure of 10 vapors generated within the tank or a partial vacuum within the tank caused by condensation, or contraction of vapor within the tank, or withdrawal of liquid therefrom, may be relieved.

15 Another object of this invention is to produce an apparatus of the character described so constructed as to prevent communication of fire to the vapors or fluid within the tank from the burning vapor outside the tank, in 20 case of ignition of the latter by lightning, or otherwise, and the apparatus also embodies an automatic snuffer designed to automatically extinguish the outside flame, in 25 case of such ignition and at the same time permit the outlet of vapor from the tank and the inlet of air into same, so as to maintain the pressures within and without the tank within certain limits so as to prevent the bursting, or collapsing of the tank.

30 With the above and other objects in view this invention has particular relation to certain novel features of construction, operation and arrangement of parts an example of which is given in this specification and illustrated in the accompanying drawings, wherein—

Figure 1 shows a vertical sectional view of the apparatus.

Figure 2 shows a horizontal sectional view 40 taken on the line 2—2 of Figure 1.

Figure 3 shows a plan view.

Figure 4 shows a vertical sectional view of the vent discharge and the automatic snuffer associated therewith, and

45 Figure 5 shows a vertical sectional view thereof taken on the line 5—5.

Referring now more particularly to the drawings, wherein like numerals of reference 50 designate similar parts in each of the figures, the numeral 1 designates a tank or reservoir which, except as hereinafter stated, is fluid tight. This may be a crude oil tank or a tank or reservoir for containing any other evaporating fluid. The apparatus, it

55 is to be understood, may be used in connection with any type of tank or reservoir

where it is desired to maintain a substantially equal pressure within and without the tank; or to prevent the bursting of the tank from excessive pressure within it or the collapsing thereof by reason of the outside air pressure; or where it is desired to safely permit the escape of inflammable vapors from the tank.

The numeral 2 designates a vent tube 65 which leads from the tank, preferably from the top, or upper part thereof.

Fastened to the outer end of this vent tube there is a valve casing 3, whose upper end is normally closed by the removable 70 screw plug 4. Formed integrally with one side of the casing 3 there is a tubular neck 5 whose outer end is flared, forming a concavo-convex flange 6, and integral with the neck there is an inwardly extending shell 7, 75 of semicircular contour, in plan view. The top and bottom of this shell have concentric circular openings 8 and 9 to receive the annular valve seats 10 and 11. These seats are anchored in fixed relation by the vertical 80 bars 12, preferably six in number, whose upper ends are also attached to the ring 13 against which the screw plug 4 abuts when screwed into place. The ring 13 has a cross bar 14, forming a handle so that when the 85 plug 4 is removed the ring 13 and the seats 10 and 11 may be removed as a unit. For this purpose the opening 8 is of a diameter to permit the passage through it, of the seat 11. When these parts are removed access to 90 the inside of the tank 1 is permitted, for measuring the fluid therein, or for other desired purposes. The upper sides of the valve seats are formed with annular knife edges, and they taper, or decline outwardly from 95 said edges. Seated on the respective seats 10 and 11 are the disc like valves 15 and 16 which are confined against lateral displacement by the stays 12 which form cages for said valves. These valves normally seat on 100 the knife edges of said valve seats and form vapor tight joints therewith and condensation collecting on said seats will run off the declining sides thereof and thus prevent the collection on said seats of any substance 105 which would tend to cause the valves to stick, or adhere, to said seats. The shell 7 is spaced from the walls of the casing 3, forming an air inlet passageway 17 into the vent tube 2.

110 Spaced screens 18, 18 are provided. These screens are clamped between the grids, or

frame, 19, 19, 19 whose margins fit against the outer margin of the flange 6 and clamped against which is the ring 20. These screens are provided to prevent the flame of the free vapor outside of the tank from being communicated to the vapor within the tank, on the well known principle.

The numeral 21 designates a hood which is secured in place by means of the clamp bolts 22 which pass through the base thereof and through the bearings 23, carried by the flange 6, and are held in place by the wing nuts 24. A foraminated metallic plate 25 is spaced outside the screens 18 and its margins are clamped between the ring 20 and the base of the hood 21. This plate is provided to protect the screens against mechanical injury, and also to keep burning vapors away from the screen. It will be noted that the clamp bolts 22 not only secure the hood 21 in place but clamp the screens 18 and their protecting plates 25 in position, as well and by loosening the nuts 23, and removing the end bolts 24, at one side, the screens 18 or plate 25, or both may be readily removed for inspection or repairs, and as readily replaced.

The structure hereinabove described, supported by the neck 5, forms a vapor outlet 30 and an air inlet. Pivoted to the ear 26, there is a lever 27 whose outer end supports a door 28 adapted to close the outer end of the hood 21. This door is pivoted to the lever 26 and has a central air inlet opening 29 which is normally closed by the inside shutter 30, which is swung from the lugs 31, through the link 32 which is pivotally connected to said lug and shutter. The door 28 is normally held in open position by means of the bars 33, 34, which are connected by a link 35 of fusible metal, the former of which is anchored to the upper part of the hood 21, and the latter of which is connected to the lever 27 behind the ear 26, by means of a chain 36. The inner end of the lever 27 carries an overbalancing weight 37, which is provided to swing the door 28 into position to close the hood 21 should the link 35 melt and separate the rods 33, 34 as hereinabove stated.

With the tank wholly or partly filled with petroleum the vaporization of the same will gradually create pressure within the tank until the pressure is sufficient to lift the valve 16, from time to time to permit the escape of the vapor. The pressure required to lift said valve will depend on the weight of the valve. The vapor thus escaping will pass out to free air through the neck 5 and the hood 21. In case the petroleum is drawn off from the tank, or of condensation or contraction of vapor therein, a partial vacuum will be created therein and the outside air pressure will lift the valve 15 and admit air into the tank through the passageway 17.

In case the gas escaping should become ignited outside of the tank, as by lightning, the flame will be arrested by the screens 18 and will not be communicated to the gas or oil in the tank. If the flame continues it will soon melt the link 35 and thereupon the weight 37 will be released and it will swing the door 28 into closed position and this will extinguish the flame.

While the door is in closed position the vapor accumulating in the tank will, from time to time, as the pressure increases, force the door 28 open, to relieve the pressure. In like manner a vacuum formed in the tank will be relieved by the inlet of additional air through the shutter opening 29.

What we claim is:

1. An apparatus adapted for application to a fluid reservoir and having a passageway provided for the exit of fluid from said reservoir and the inlet of air into the reservoir, valve seats in said passageway, valves cooperating with said seats and controlling said passageways, one of said valves being adapted to open under the influence of pressure outwardly from said reservoir, through said passageway, the other of said valves being adapted to open under the influence of fluid pressure in the opposite direction through said passageway, swinging doors adapted to close said passageway and one of which is arranged to normally be held closed by gravity, means tending to swing the other door into closed position and means including a fusible link normally holding the last named door open. 95

2. An apparatus adapted for application to a fluid reservoir and having a passageway provided for the exit of fluid from said reservoir and the inlet of air into the reservoir, valve seats in said passageway, valves cooperating with said seats and controlling said passageways, one of said valves being adapted to open under the influence of pressure outwardly from said reservoir, through said passageway, the other of said valves being adapted to open under the influence of fluid pressure in the opposite direction through said passageway, a door adapted to close the outer end of said passageway and formed with an inlet opening, an inwardly opening shutter mounted to be held by gravity in position to normally close said opening, releasable means normally holding the door in open-position and means normally tending to close said door. 110

3. An apparatus adapted for application to a fluid reservoir and having a passageway provided for the exit of fluid from said reservoir and the inlet of air into the reservoir, valve seats in said passageway, valves cooperating with said seats and controlling said passageways, one of said valves being adapted to open under the influence of pressure outwardly from said reservoir, through 125

- said passageway, the other of said valves being adapted to open under the influence of fluid pressure in the opposite direction through said passageway, a foraminated partition spanning said passageway, said valves being between the partition and reservoir, doors adapted to close the outer end of the passageway, one of which is mounted to be closed by gravity, means tending to 5 swing the other door into closed position, means including a fusible link and normally holding the last named door in open position.
4. An apparatus adapted for application to a fluid reservoir and having a passageway 15 provided for the exit of fluid from said reservoir and the inlet of air into the reservoir, valve seats in said passageway, valves cooperating with said seats and controlling said passageways, one of said valves being 20 adapted to open under the influence of pressure outwardly from said reservoir, through said passageway, the other of said valves being adapted to open under the influence of fluid pressure in the opposite direction 25 through said passageway, a foraminated partition spanning said passageway, said valves being between the partition and reservoir, doors adapted to close the outer end of the passageway, one of which is mounted to 30 be closed by gravity, means tending to swing the other door into closed position, means in- cluding a fusible link and normally holding the last named door in open position, and a perforated plate spanning the passageway between the door and said partition. 35
5. An apparatus adapted for application to a fluid reservoir and having a passageway provided for the exit of fluid from said reservoir and the inlet of air into the reservoir, valve seats in said passageway, valves 40 cooperating with said seats and controlling said passageways, one of said valves being adapted to open under the influence of pressure outwardly from said reservoir, through said passageway, the other of said valves being adapted to open under the influence of fluid pressure in the opposite direction through said passageway, a foraminated partition spanning said passageway, said valves being between the partition and reservoir, a 45 door adapted to close the outer end of said passageway and formed with an inlet opening, an inwardly opening shutter adapted to normally close said opening, releasable means normally holding the door open and means for actuating the door into closed position upon release of said releasable means. 50
- In testimony whereof we have signed our names to this specification.

GEORGE C. SCHMIDT.
FRANS G. D. MULLER.
